(57) **CLAIM**

The ornamental design for a display device, as shown and described.

DESCRIPTION

FIG. 1 is a front perspective view of a display device showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is an enlarged view of the upper right corner marked “8” in FIG. 1; and,

FIG. 9 is an enlarged view of the upper left corner marked “9” in FIG. 4.

Broken lines illustrate portions of the display device that form no part of the claimed design. Stippling and straight-line shading represent a contrast in appearance on surfaces of the display device.
